UNITED STATES PATENT OFFICE

2,480,330

BUILDING METHOD AND CONSTRUCTION

Ernest J. Kump, Atherton, Calif.

Application June 19, 1945, Serial No. 600,286

7 Claims. (Cl. 20—2)

1

The present invention relates to a building frame structure and to a method erecting a building frame on a floor from frame members of the type as shown in my United States Letters Patent No. 2,413,145 of December 24, 1946, or of the general type disclosed in United States Letters Patent to Horn et al., No. 2,283,193, of June 30, 1942. These frame members each consist of a stud and rafter integrally united and free from braces or the like and sufficiently strong so that the rafter projecting laterally from the upper end of the stud requires no support during manipulation of each frame member to prevent its distortion or bending under its own weight.

One of the objects of this invention is an improved method of erecting a building frame using frame members of the type above described whereby only several workmen may more quickly erect such frame than heretofore.

Another object of the invention is the provision of an improved building frame formed from frame members of the type described above that is of simple construction and in which the frame members are accurately and positively secured in predetermined spaced relation so that further operations such as panelling and roofing may be accurately accomplished with precut or preformed panels whereby the frame may be used in prebuilt or prefabricated building structure.

Other objects and advantages will appear in the description and in the drawings.

In the drawings,

Fig. 1 is a perspective view illustrative of several steps in the method of erecting the frame.

Fig. 2 is an enlarged fragmentary view showing the ridge structure at a splice from one side of the ridge.

Fig. 3 is a fragmentary plan view of the portion shown in Fig. 2.

Fig. 4 is a vertical sectional view taken through the ridge pieces.

Fig. 5 is an enlarged fragmentary sectional view taken vertically through a floor plate.

Fig. 6 is a fragmentary elevational view taken from outside the building showing the notched floor plate with the bottom end of the stud therein.

Fig. 7 is an enlarged fragmentary vertical sectional view taken through one of the shoulder pieces at the juncture between the stud and rafter of each frame member.

Fig. 8 is a fragmentary elevational plan view showing the shoulder of the frame member in a notch formed in the shoulder piece.

Before giving a detailed description of the

2

method employed in erecting the building frame of the invention the structure itself will be described, it being understood that the detailed description and the drawings are not to be considered restrictive of the invention.

10 Each frame member generally designated 1 is preferably formed of plywood as described in my aforesaid co-pending application and in Figs. 2, 3, 6 and 8 the plurality of plies 2 forming each frame member are indicated.

Each frame member comprises a stud 3 and a rafter 4 (Fig. 1) integrally and inseparably united at their adjacent ends free from extraneous braces or the like inasmuch as the arrangement 15 of the plies of wood in each frame member are parallel with the plane common to the stud and rafter whereby the rafter requires no support during manipulation of the stud to prevent bending under its own weight.

20 A pair of rows of said frame members is adapted to be supported on floor 5 of the building with the lower ends of the studs 3 of each row along floor plates 6 that are along two opposite edges of said floor.

25 The lower ends of each of said studs is formed with a right angle corner notch 7 (Fig. 5) along the lower outer edge of each stud and each floor plate 6 is formed with a notch 9 (Fig. 6) in its upper side in which the upper edge 10 of each notch 7 is adapted to fit. The unnotched lower forward corner of each stud extends across the inner side of each floor plate to the floor or substantially to said floor.

30 By this structure it is not possible for the base 35 or lower ends of the studs to move outwardly relative to the center of the floor because the forward or vertical edges 12 of the notches 7 in said studs (Fig. 5) engage the lateral inner surface of each floor plate. Nor can the studs in each row move toward or away from each other at their lower ends inasmuch as they are held in notches 9 in the floor plate. The notches 9 may very readily be cut to provide absolutely accurate spacing between notches thereby insuring absolute accuracy in the positioning of the lower ends 40 of the studs.

45 The shoulders of the frame members are notched out at 15 providing an upwardly facing edge 16 and an outwardly facing edge 17. A shoulder piece 20 that may practically be a duplicate of the floor plate (but inverted) and having notches 21 therein (Figs. 1, 7) spaced identical with the notches in the floor plate is positioned in notches 15 with the upper edges 16 of said notches in each of the notches 21 in the shoulder

piece. By this structure the frame members are rigidly held at the junctures between the rafters and studs in identically the same spaced relationship as the lower ends of the studs. Vertical screws 22 extend through the shoulder pieces into the frame members holding the edge 16 securely on notch 21.

Extending across the outer ends of the rafters of one row of frame members is a ridge piece 25 while a ridge piece 26 extends across the outer ends of the rafters of the other row. There are generally several of said ridge pieces required for each row where the building frame is relatively long and in such instances the ridge pieces 25, 26 are arranged in pairs in opposed relation and so that one ridge piece such as 25 (Fig. 3) projects beyond the adjacent end of the adjacent ridge piece 26. The adjacent pair of ridge pieces in direction longitudinally of said pieces and of the rows of frame members are positioned so that ridge piece 26 will overlap the projecting end of ridge piece 25. Thus by connecting these overlapping ends with screws 28 (Figs. 2, 3) a strong splice is made.

Each ridge piece 25 and each ridge piece 26 is formed with notches 29 in which the outer ends of the rafters of the respective rows of frame members are fitted. Screws 30 may secure the ridge pieces 25 to the rafters of the left-hand row (Figs. 1, 4) while screws 31 secure the ridge pieces 26 to the rafters of the right-hand row. The said ridge pieces are of course secured to the rafters before the splices already described are made and after said ridge pieces are so secured to the respective rafters of the two rows the said ridge pieces 25, 26 are secured together by screws 33 (Fig. 2). Then screws 28 connect the splices.

The foregoing structure insures a rigid and extremely accurate positioning of the frame members and is particularly suited to prefabrication of parts so that the frame members may be accurately and quickly set up at the building site and when so set up there can be no variation in spacing between the frame members or between the studs and rafters.

The method of erecting the building frame is particularly important inasmuch as formerly with the type of structure generally described herein it had been customary to erect the frame members one at a time and to employ various expedients for holding the frame members in place.

By the present invention the frame members may be first arranged in a row along each of the base plates with the lower ends of the studs in each notch 9. Thus the lower ends of the studs are properly spaced even before the frame members are erected.

The ridge pieces 25, 26 may be secured in place over the outer ends of the rafters and as said outer ends extend past each other it will be seen (Fig. 1) that one of the ridge pieces, for example ridge piece 25, may be on the floor while the other ridge piece 26 rests on the rafters of the frame members that are connected by said pieces 25.

The shoulder strips or pieces 20 may connect and space the frame members at their shoulders but where splicing of the shoulder pieces is to be avoided any strips such as a piece of scantling 30 may temporarily secure the frame members in spaced relation adjacent the shoulders if desired.

The frame members secured together as above described are preferably in groups of three or

four as seen in the forepart of Fig. 1 and after they are so secured together the one group, such as the frame members connected by ridge piece 26, may be elevated as a unit by one or two men.

Once this group is elevated the group on the other side, such as frame members connected by ridge piece 25, are elevated to a position in which the ridge pieces 25, 26 are in opposed relation as is seen in the rear groups in Fig. 1. The ridge pieces 25, 26 may then be readily secured together and unless the shoulder pieces 20 are previously secured on the frame members of each group such pieces may be secured to the said members.

15 This securing of the frame members of each pair of opposite groups together by separate ridge pieces is relatively important since the ridge pieces 25, 26 when brought into opposed relationship are very easily adjusted relative to each other, whereas were a single ridge piece used the adjustment of each opposite pair of frame members to the single piece is quite difficult.

I claim:

1. The method of erecting a building frame 25 on a floor from frame members each of which comprises an integrally united stud and rafter and which floor has spaced parallel floor plates along two of its opposite edges, said method comprising the steps of securing a row of said frame members together in equally spaced parallel relationship over said floor and inwardly between said floor plates and along each of the latter with said frame members tilted so that the rafters of one row of frame members overlie the rafters 30 of the other row of frame members centrally between said floor plates, then swinging said rows of frame members to elevated position about axes respectively substantially coincident with said floor plates so that the outer ends of said rafters 35 outwardly of said studs are in elevated opposed relation centrally over said floor, then rigidly securing said outer ends in said opposed relation.

2. The method of erecting a building frame on

a floor from frame members each of which comprises an integrally united stud and rafter and which floor has parallel floor plates along two of its opposite edges, said method comprising the steps of securing a row of said frame members together in equally spaced parallel relationship over said floor and inwardly between said floor plates by securing the outer ends of the rafters of one row to a ridge piece extending across said ends and by securing the outer ends of the rafters of the other row to another ridge piece extending across said latter ends, supporting the respective rows of frame members so secured together in each row with the stud members tilted toward the center of the floor and with the outer end portions of the rafters of one of said rows overlying the similar end portions of the rafters of the other row, then swinging said rows one after the other to elevated position about axes respectively substantially coincident with said floor plates and to positions with said roof pieces together in horizontally opposed relation, then securing said ridge pieces together.

3. The method of erecting a building frame on a floor having parallel floor plates along two opposite edges thereof and from frame members each of which comprises an integrally joined stud and rafter that comprises the steps of securing rows of said frame members in equally spaced relationship along each of said floor plates with the lower free ends of the studs of said frame members against such floor plates

and with the outer ends of the rafters of one row of frame members supported on the rafters of the other row and with the outer ends of the rafters of said other row supported on said floor, then swinging the said one row of frame members as a unit to elevated position about an axis substantially coincident with the floor plate adjacent said row and thereafter swinging the said other row to elevated position in which the outer ends of the rafters thereof are in opposed relationship to the outer ends of the rafters of said one row, then rigidly securing the frame members of both rows together with the outer ends of their rafters in said opposed relationship.

4. In a building frame having a pair of parallel rows of frame members each of which members comprises an integrally joined stud and rafter providing a shoulder at their juncture, ridge pieces in opposed relation respectively extending across the outer ends of the rafters of a plurality of pairs thereof in each row and secured to the rafters of each row, means securing the opposed ridge pieces together and each of said ridge pieces being formed with uniformly spaced notches in the oppositely outwardly facing sides of the joined ridge pieces in which the adjacent rafter ends are fitted, the notches in one of said ridge pieces being directly opposite the notches in the other ridge piece that is secured thereto, shoulder pieces extending longitudinally of each row formed with notches in which the shoulders of said frame members are fitted, said notches in each shoulder piece having the same spacing as the notches in said ridge piece, and floor plates along the lower ends of the studs of each row being formed with notches in which a portion of said lower ends are fitted, said notches in each floor plate having the same spacing as the spacing of the notches in each of said shoulder pieces and ridge pieces, the notches in said ridge pieces, shoulder pieces and floor plates being disposed in parallel vertical planes whereby said frame members will be rigidly secured in spaced relation along the outer ends of the rafters and studs relative to said shoulders and will be securely held in parallel, vertical planes and along said shoulders.

5. In a building frame having a pair of parallel rows of frame members each of which members comprises an integrally joined stud and rafter providing a shoulder at their juncture, ridge pieces in opposed relation respectively extending across the outer ends of the rafters of a plurality of pairs thereof in each row and secured to the rafters of each row, means securing the opposed ridge pieces together and each of said ridge pieces being formed with uniformly spaced notches in the oppositely outwardly facing sides of the joined ridge pieces in which the adjacent rafter ends are fitted, the notches in one of said ridge pieces being directly opposite the notches in the other ridge piece that is secured thereto, shoulder pieces extending longitudinally of each row formed with notches in which the shoulders of said frame members are fitted, said notches in each shoulder piece having the same spacing as the notches in said ridge piece, and floor plates along the lower ends of the studs of each row being formed with notches in which a portion of said lower ends are fitted, said notches in each floor plate having the same spacing as the spacing of the notches in each of said shoulder pieces and ridge pieces, the notches in said

ridge pieces, shoulder pieces and floor plates being disposed in parallel vertical planes whereby said frame members will be rigidly secured in spaced relation along the outer ends of the rafters and studs relative to said shoulders and will be securely held in parallel, vertical planes and along said shoulders, said shoulders and said lower ends of said studs being notched complementary to the notches in said shoulder pieces and floor plates.

5 6. In a building frame, a pair of parallel rows of frame members each of which members comprises an integrally joined stud and rafter, several pairs of longitudinally aligned ridge pieces 15 respectively secured to the outer adjacent ends of the rafters of said rows securing a plurality of the rafters in each row in predetermined spaced relation, the ridge pieces of each of said pairs being longitudinally offset so that one end portion of one ridge piece in each pair projects beyond the adjacent end of the other ridge piece, and the projecting ends of the ridge pieces of adjacent pairs being in overlapping relation to provide a splice joint between the adjacent pairs 20 of ridge pieces, means for securing the projecting overlapping ends of said ridge pieces together, and means for securing the ridge pieces of each pair to each other.

7. In a building frame, a pair of parallel rows 25 of frame members each of which members comprises an integrally joined stud and rafter, several pairs of longitudinally aligned ridge pieces respectively secured to the outer adjacent ends of the rafters of said rows securing a plurality 30 of the rafters in each row to predetermined spaced relation, the ridge pieces of each of said pairs being longitudinally offset so that one end portion of one ridge pieces in each pair projects beyond the adjacent end of the other ridge piece, and the projecting ends of the ridge pieces of adjacent pairs being in overlapping relation to provide a splice joint between the adjacent pairs 35 of ridge pieces, means for securing the projecting overlapping ends of said ridge pieces together, and means for securing the ridge pieces of each pair to each other, the ridge pieces of each pair being notched transversely and the said outer ends of said rafters being secured in 40 said notches.

50 ERNEST J. KUMP.
